Strong & Townsend
ATTORNEY

UNITED STATES PATENT OFFICE.

FRED FOURNIER, OF SAN FRANCISCO, CALIFORNIA.

REVERSIBLE WINDOW.

1,341,366.

Specification of Letters Patent. Patented May 25, 1920.

Application filed February 26, 1919. Serial No. 279,241.

To all whom it may concern:

Be it known that I, FRED FOURNIER, a citizen of the United States, residing at San Francisco, in the county of San Francisco, 5 and State of California, have invented new and useful Improvements in Reversible Windows, of which the following is a specification.

This invention relates to a window construction, and particularly pertains to a reversible window mounting. It is often desirable to easily reach the outer surface of a window pane, especially when the window is being washed and it is also of advantage 15 to be able to reverse a window sash in order to supply it with a window pane. This is especially true when the windows are at considerable height and cannot be reached without danger.

It is the principal object of the present invention to provide a simple mounting for a window sash which will permit the window to be readily opened when desired and will insure that it may be instantly reversed 25 without the manipulation or removal of any parts and by direct action of the sash.

It is a further object of this invention to provide an automatic means for locking the window in position so that it will not rattle 30 when closed and will not readily become displaced when opened.

Other objects of the invention will appear hereinafter.

The invention is illustrated by way of example in the accompanying drawings, in which—

Figure 1 is a view in front elevation, disclosing a window sash fitted with the reversible mechanism, parts of which are broken 40 away to more clearly show the construction.

Fig. 2 is a view in vertical section on line 2—2 of Fig. 1, showing the complete sash mounting.

Fig. 3 is a view in section and elevation 45 as seen on line 3—3 of Fig. 1, illustrating the lock provided for the window, and also indicating by dotted lines the reversed position of the window.

Referring more particularly to the drawings, 50 indicates a window frame. Mounted within this frame is a sash 11, which sash is designed to normally close the opening in the frame and to rest against stops 12. Secured at the upper and lower ends of the 55 sash rails and at the corners of the sash, are hinge plates 13 and 14. These plates pro-

ject outwardly and are perforated to receive a reversing shaft 15. The shaft 15 extends through the perforations in these plates and may freely rotate. Fixed to the upper end 60 of this shaft is a spur gear 16, having a lower hub which directly rests upon the plate 13. Fixed to the lower end of the shaft is a spur gear 17 identical with the upper gear. The upper spur gear is in constant mesh with the gear rack 18 secured across the top of the window frame and disposed within a suitable recess formed for the purpose. This recess is covered by a shroud which has a forwardly and downwardly extended plate standing parallel and in spaced relation to the rack. This plate completely conceals the spur gear 16 and the rack 18, at the same time providing a guide-way for a roller 20 which is mounted above 75 the gear 16 and is free to rotate on the shaft 15. This roller acts to hold the gear 16 in constant mesh with the rack 18.

At the lower end of the shaft 15, the gear 17 is in constant mesh with a rack 21 fixed 80 to the sash. By referring to Fig. 2, it will be seen that the shaft 15 does not extend completely through the gear 17 but is formed with a reduced portion 22 situated within a saddle member 23. This saddle is 85 formed with a cylindrical protrusion extending into the gear and counter-bored to receive the portion 22 of the shaft, thus insuring that the saddle will move in unison with the shaft and gear as they travel along 90 the gear rack 21. The saddle rests upon a guide bar 24 fixed to the sill of the window. This saddle also has a downwardly projecting flange extending along the rear face of the guide bar 24, thus holding the gear 17 in 95 mesh with the rack bar 21, at the same time allowing the saddle to slide along the bar.

Reference being had to Fig. 3, it will be seen that side rail 25 of the sash is provided with a locking hook 26 formed integral with a fastening plate 27, this plate being counter-sunk within the side face of the rail and holding the hook so that it will swing in a horizontal plane as the sash rotates upon the axis of the shaft 15, 105 thus insuring that as the window is closed, this hook will swing into an opening in a lock plate 28. The lock plate 28 is counter-sunk and secured to the face of the window frame adjacent the rail 25. Thus, when the 110 window is closed and is in its normal position, it will be locked against rattling and

may be further secured by means of any suitable window lock 29, this lock, of course, being preferably mounted upon the opposite side rail 30 of the window sash.

5 In operation, it will be assumed that the window is closed and that the hook 26 is in engagement with the plate 28. If it is desired to open the window, the fastener 29 may be released and the window may 10 then be swung outwardly upon the axis of the shaft 15. If it is desired to open the window and dispose it at any point in the width of the frame, this may be easily done by applying pressure to the shaft 15. This 15 will cause the shaft to rotate and the upper and lower gears 16 and 17 respectively, to travel along their gear racks and in the direction of the arrows *a*, as indicated in Fig. 1.

20 While the shaft is thus traveling, the roller 20 will bear against the inner face of the shroud plate 19 and the saddle member 23 will slide along the guide bar 24. At any point intermediate the extreme ends 25 of the racks, the window may be swung outwardly and will pivot upon the shaft. When the shaft and gears have reached the opposite side of the window from their normal position, the window sash may be completely reversed and caused to assume the 30 position indicated by dotted lines in Fig. 3. When so reversed, it will be evident that access to the outer surface of the window pane may be easily had. When the window 35 is to be closed, the shaft with its gears are moved across the window pane in a reverse direction and when they have reached the end of their travel the sash may be swung inwardly. This will cause the hook member 40 26 to register with the opening in the plate 28 and make contact in a manner to hold the sash against rattling and the latch 29 may then be closed, if desired.

It will thus be seen that the sash mounting here disclosed, while simple in construction and capable of being easily installed, provides means for readily opening a window and permitting the sash thereof to be partially or completely reversed, as the occasion demands.

While I have shown the preferred form of my invention, it will be understood that various changes in the combination, construction and arrangement of parts may be 55 made by those skilled in the art, without departing from the spirit of the invention as claimed.

Having thus described my invention, what I claim and desire to secure by Letters Patent is—

1. In combination with a window frame and its sash, hinge plates secured to the top and bottom of said sash, and adjacent one corner thereof, a hinge rod extending vertically through both of said plates, a pair of

gears, one of which is fixed to each of the opposite outer ends of said rod, gear racks secured in parallel relation to each other to the outer face of the window frame and with which said gears are adapted to constantly mesh, a flanged saddle member within which the lower end of the rod is freely rotatable and a guide bar along which the saddle member is adapted to slide and by which the lower end of the rod is held in 75 movable relation to the frame along a fixed path of travel.

2. In combination with a window sash and a frame therefor having stops against which the inner face of the sash may rest, 80 a pair of gear racks secured to the outer faces of the frame and at the top and bottom of the frame opening respectively, a pair of gears, one of which meshes with each of the racks, a vertically disposed hinge 85 shaft to the opposite ends of which the gears are secured, hinge plates secured to the top and bottom of the window-sash and adjacent the corners thereof and through which the shaft is adapted to freely rotate, a 90 flanged saddle member provided with a cup within which the lower end of the hinge shaft is adapted to seat and rotate, a guide-bar disposed beneath said saddle member and extending transversely of the frame 95 parallel to the gear rack, and means including a flange for preventing the displacement of said saddle member other than to permit it to travel along said guide bar.

3. In combination with a window sash 100 and a frame therefor having stops against which the inner face of the sash may rest, a pair of gear racks secured to the outer faces of the frame and at the top and bottom of the frame opening, respectively, a 105 pair of gears, one of which meshes with each of the racks, a vertically disposed hinge shaft, to the opposite ends of which the gears are secured, hinge plates secured to the top and bottom of the window sash and 110 adjacent the corners thereof and through which the shaft is adapted to freely rotate, a saddle member provided with a cup within which the lower end of the hinge shaft is adapted to seat and rotate, a guide-bar 115 disposed beneath said saddle member and extending transversely of the frame parallel to the gear-rack and a flange along one side of the saddle member for preventing the displacement of said saddle member, 120 other than to permit it to travel along said rail, a roller freely mounted upon the upper end of the shaft and an angle-shaped shroud adapted to extend outwardly and downwardly over the roller and the upper 125 gear to conceal the same and to provide a bearing surface for said roller.

4. In combination with a window sash and a frame therefor, a pair of hinge plates secured to the top and bottom of said 130

- sash and extending outwardly from a point near the corner thereof, a hinge shaft extending through said plates, a saddle member within which the lower end of the shaft projects and rotates, a guide-bar extending transversely of the window frame and along which said saddle member may slide to support the weight of the sash and guide the same, gears fixed to the opposite ends of said shaft, racks extending along the outer face of the window frame and at the top and bottom of the sash for constant meshing with the gears, a flange formed upon the saddle member and adapted to interlock between the lowermost rack and the guide-rail to prevent removal of the saddle from said rail, a roller freely mounted upon the upper end of the hinge shaft, and an angle-shaped shroud plate extending over the roller and downwardly to conceal the roller and the upper gear and to provide a trackway for said roller.
5. In combination with a window sash and a frame therefor, a pair of hinge plates secured to the top and bottom of said sash and extending outwardly from a point near the corner thereof, a hinge shaft extending through said plates, a saddle member within which the lower end of the shaft projects and rotates, a guide-bar extending transversely of the window frame and along which said saddle member may slide to support the weight of the sash and guide the same, gears fixed to the opposite ends of said shaft, racks extending along the outer face of the window frame and at the top and bottom of the sash for constant meshing with the gears, a flange formed upon the saddle member and adapted to interlock between the lowermost rack and the guide-rail to prevent removal of the saddle from said rail, a roller freely mounted upon the upper end of the hinge shaft, and an angle-shaped shroud plate extending over the roller and downwardly to conceal the roller and the upper gear and to provide a trackway for said roller.
10. said shaft, racks carried along the outer face of the window frame and at the top and bottom of the sash for constant meshing with the gears, a flange formed upon the saddle member and adapted to interlock between the lowermost rack and the guide-rail to prevent removal of the saddle from said rail, a roller freely mounted upon the upper end of the hinge shaft, and an angle-shaped shroud plate extending over the roller and downwardly to conceal the roller and the upper gear and to provide a trackway for said roller.
15. tween the lowermost rack and the guide-rail to prevent removal of the saddle from said rail, a roller freely mounted upon the upper end of the hinge shaft, and an angle-shaped shroud plate extending over the roller and downwardly to conceal the roller and the upper gear and to provide a trackway for said roller.
20. and downwardly to conceal the roller and the upper gear and to provide a trackway for said roller.
25. In combination with a window sash and a frame therefor, a pair of hinge plates secured to the top and bottom of said sash and extending outwardly from a point near the corner thereof, a hinge shaft extending through said plates, a saddle member within which the lower end of the shaft projects and rotates, a guide-bar extending transversely of the window frame and along which said saddle member may slide to support the weight of the sash and guide the same, gears fixed to the opposite ends of said shaft, racks extending along the outer face of the window frame and at the top and bottom of the sash for constant meshing with the gears, a flange formed upon the saddle member and adapted to interlock between the lowermost rack and the guide-rail to prevent removal of the saddle from said rail, a roller freely mounted upon the upper end of the hinge shaft, and an angle-shaped shroud plate extending over the roller and downwardly to conceal the roller and the upper gear and to provide a trackway for said roller.
30. and downwardly to conceal the roller and the upper gear and to provide a trackway for said roller.

In testimony whereof I have hereunto set my hand in the presence of two subscribing witnesses.
